FREE EDGE WAISTBAND FOR GIRDLES
Simon Grishman, Yonkers, N.Y., assignor to William Gluckin & Company, Inc., New York, N.Y., a corporation of New York

Filed July 29, 1963, Ser. No. 298,131
3 Claims. (Cl. 128—519)

This invention relates to girdles and, more particularly, to the manner of attaching the waistband to the upper edge portion of the girdle, so as to leave the major portion of the waistband unattached for free and independent movement in providing a more positive support of the girdle upon the body of the wearer.

Still more particularly, the invention deals with girdles of the character described, wherein a panty is freely disposed within the body portion of the girdle, with the upper portion of the panty fixed to the girdle body where the waistband is attached thereto.

The novel features of the invention will be best understood from the following description, when taken together with the accompanying drawing, in which certain embodiments of the invention are disclosed and, in which, the separate parts are designated by suitable reference characters in each of the views and, in which:

FIG. 1 is a diagrammatic front view of a girdle made according to my invention, with the body parts disposed substantially one directly upon the other, with part of the construction broken away and illustrating, in part, types of stitchings employed, as well as finished edging to the waistband.

FIG. 2 is a rear view of the girdle as seen in FIG. 1.
FIG. 3 is an enlarged partial section on the line 3—3 of FIG. 1, diagrammatically illustrating the stitching.

FIG. 4 is an enlarged partial section on the line 4—4 of FIG. 1, again diagrammatically illustrating the stitching and omitting detail showing of a front seam; and

FIG. 5 is an enlarged partial section on the line 5—5 of FIG. 1, diagrammatically showing more clearly the front seam of the girdle body.

While my invention is adapted for use in conjunction with girdles of various types and kinds, in the present disclosure, I have shown one adaptation in what is generally referred to as a panty girdle.

The girdle, as shown, may be said to comprise five basic components or parts, namely the girdle body 10, a panty 11, a waistband of extensible material 12, a front reinforcing panel 13, the general contour of which is indicated in dotted lines in FIG. 1, and a back panel 14, again, the general contour of which is illustrated in FIG. 2 of the drawing. While garters usually employed are a component part, in order to simplify the showing the illustration of the garters has been eliminated, but the garters attached to the front of the body portion 10 are diagrammatically represented by the dot-dash lines 15 and the garters attached to the rear of the body 10 are indicated by the dot-dash lines 16.

The girdle body 10 is formed primarily of two members 17 and 18, joined at the back in a seam and contoured to form the desired fullness in the lower portion of the back, the seam preferably including extensible stitchings, as indicated, in part, at 19 in FIG. 2 of the drawing. The front edge portions of the members are folded-over and joined by a spaced extensible stitching, as diagrammatically seen at 20 in FIG. 5, and part of this stitching is indicated in FIG. 1. This construction actually provides between the front edges of 17 and 18 a slight space, as will clearly appear from a consideration of FIG. 5. In view of the showing in FIG. 5, no attempt has been made to repeat this showing in FIG. 4 of the drawing. In FIG. 4, the stitching 20 is shown by the single

2

line 20'. The members 17 and 18 of the body 10 are formed of all-way stretch material and lower edge portions of these members are finished with elastic edgings, as diagrammatically illustrated at 21 and 22 in FIGS. 1 and 2 of the drawing. The upper edges 23 and 24 of the members 17 and 18 terminate short of the upper edge 25 of the waistband 12 and these upper edges are stitched to the waistband by a contoured-type of extensible stitching illustrated, in part, at 26 in FIG. 1 of the drawing. This produces a neat and finished appearance and this appearance is further characterized by a special scallop-type strand edging 27 projecting from the upper edge 25 of the waistband 12.

From the foregoing, it will be apparent that the waistband 12 is attached at its upper edge to the upper edges 23 and 24 of the girdle body 10 and this stitching is diagrammatically illustrated by the stitch line 26' in FIG. 3 of the drawing. This leaves the remainder lower portion of the waistband, and in fact the major portion of the waistband, free for independent body engagement and support of the girdle upon the body of the wearer. Due to the projection of the upper portion of the waistband 12, it may be said that the entire waistband, aside from the stitchings 26, is free to engage the body of the wearer.

The panty 11 or the upper edge portion thereof is arranged between the waistband and the body 10, as clearly noted in FIG. 3 of the drawing, and is secured in position by the stitching 26. In the construction shown, the panty 11 is preferably formed of a soft all-way stretch tubular material, cut to form the two leg openings 28 and 29, the opening 28 being shown only in part in FIG. 1 and the lower edge portion of the panty is seamed with an extensible seam, illustrated, in part, at 30 in FIG. 1 of the drawing.

The panels 13 and 14 are preferably made of an all-way stretch material, which could be the same material as that employed in the girdle body 10. The panel 13 is generally of arrowhead contour and is located at the upper portion of the girdle body, the contracted upper end 13' of which extends to the upper edges 23, 24 of the members 17 and 18, as clearly noted in FIG. 1. The periphery of the panel 13 is secured to 17 and 18 by extensible stitchings illustrated, in part, at 31 in FIG. 1. However, the remainder of the panel is unattached, as will clearly appear from a consideration of FIG. 4 of the drawing, where the seams 19 and 21 do not extend into the panels 14 and 13 respectively, the stitchings of the panel 13 being indicated at 31; whereas, similar stitchings 32 at the peripheral edges of the panel 14 are also indicated and these extensible stitchings are shown, in part, in FIG. 2 of the drawing. The panel 14 is located at the lower portion of the back of the girdle and would also have in it the fullness conforming to the fullness of the body portion 10, which would be provided between the upper end 33 of the panel and the lower end 34 thereof. This fullness is provided for proper fit of the girdle upon the body of the wearer.

Considering FIG. 5 of the drawing, it will appear that the waistband 12 is a continuous elastic band and the ends of this band are overlapped and attached by the stitching 19 and this stitching 19 extends the full depth of the waistband 12, so that the upper edge portion of the back of the panty 11 would be similarly attached. By extending this stitching through the full depth of the waistband 12, the waistband is maintained in substantially parallelism with the upper back portion of the girdle at all times.

From the foregoing, it will be apparent that, in the use of the girdle, the waistband will independently and snugly engage the body of the wearer; whereas, the girdle body 10, as well as the panty, is suspended from the upper edge portion of the waistband. This construction

will provide free and independent movement of the girdle body 10, as well as the panty with respect to the waistband and, in fact, with respect to each other.

Having fully described my invention, what I claim as new and desire to secure by Letters Patent is:

1. A garment of the character defined comprising a girdle body of extensible material, a panty of extensible material disposed within the girdle body and secured thereto by stitching to its upper edge portion only, an extensible waistband on the inner surface of the upper edge portion of said panty, the upper edge portion only of the waistband being stitched to the upper edge portion of the girdle body and panty by said first named stitching, leaving the major portion of the waistband free for independent support of the garment upon the body of the wearer, and the stitching of the waistband to the girdle body and panty comprising an extensible stitching.

2. A garment as defined in claim 1, wherein the upper edge of the waistband protrudes slightly above the upper edge portion of the girdle body.

5 3. A garment as defined in claim 1, wherein the girdle body comprises two generally similar side members seamed centrally of the front and rear of the garment in extensible stitchings, and the front and rear central portions

5 of the girdle body including reinforcing panels of extensible material overlying the front and rear stitchings and movable independently of said side members.
